DESIGN FOR A WEIGHING SCALE

Morton Tucker, Collingswood, N. J.

Application February 9, 1933. Serial No. 47,164

Term of patent 7 years

To all whom it may concern:

Be it known that I, MORTON TUCKER, a citizen of the United States, and a resident of Collingswood, county of Camden, State of New Jersey, have invented a new, original, and ornamental Design for a Weighing Scale, of which the following is a specification, reference being had to the accompanying drawing, forming a part thereof, wherein:

Figure 1 is a perspective view of the weighing scale;

Figure 2 is a side elevational view thereof; and
Figure 3 is a top plan view thereof.

I claim:

The ornamental design for a weighing scale as shown.

MORTON TUCKER.
